UNITED STATES PATENT OFFICE.

THOMAS W. VARLEY, OF NEW YORK, N. Y.

DEVICE OF EXPANDED METAL.

1,228,853.

Specification of Letters Patent. Patented June 5, 1917.

Application filed February 24, 1915. Serial No. 10,281.

To all whom it may concern:

Be it known that I, THOMAS W. VARLEY, a citizen of the United States of America, and resident of the borough of Manhattan, 5 city, county, and State of New York, have invented certain new and useful Improvements in Devices of Expanded Metal, of which the following is a specification.

My invention relates to certain new and 10 useful improvements in devices of expanded metal such as guards for fans and the like and has particular reference to guards for electric fans. The object of the invention is to produce such a device which will be 15 cheap and easy of manufacture, and strong and effective in use.

In the following I have described, in connection with the accompanying drawings, a device illustrating one form of my invention, the features thereof being more particularly pointed out hereinafter in the claims.

In the drawings, Figure 1 is a perspective view of a fan guard illustrating my 25 invention and Fig. 2 is a side view of the same.

Similar numerals of reference indicate similar parts throughout the several views.

The device illustrated represents a fan 30 guard and comprises a central circular ring or rim 3 shown here as standing substantially at right angles to the plane of the face of the guard. Arms 4, 4 radiate from rim 3, are divided intermediate their length 35 to form the edges 5, 5 of openings 6, and terminate at attachment means 7, 7 which latter serve for the mounting of the guard on the fan standard (not shown). The entire fan guard, as shown, is expanded from 40 a single piece of suitable material, such as thin sheet steel, the free ends being fastened together at 8 and 9 by any suitable means as by spot welding. As is obvious from the drawings those portions of arms 4, 4 45 extending from rim 3 to the outer edge of openings 6 comprise the front face of the guard; the openings 6 bounded by edges 5, 5 comprise the circular face or side of the guard and those portions of arms 4, 4 50 extending from the inner angle of openings 6 to the attachment means 7 comprise the rear face of the guard.

The arms 4, 4 either of the front face or the rear face, preferably both faces, may 55 be twisted to present their edges to the air currents passing through the guard and

thus to offer a minimum of resistance to such air currents. The attachment means 7 may be perforated as at 10 to provide screw holes for the ready securing of the 60 guard to the standard (not shown). The arms 4, 4 where terminating in attachment means 7 are preferably divided into groups and said groups spaced from each other to provide for passing the guard over the fan 65 in placing the guard in position. The arms comprising the rear face are also shown as bent rearwardly from the vertical plane of the guard, as clearly seen in Fig. 2, while the arms comprising the front face lie in 70 a vertical plane as shown.

Each of arms 4, except those united by the welding at 9, at a point intermediate the points of division to form edges 5, 5 for openings 6, is left integral with the adjacent 75 arm 4 so as to form the connection 11 between the adjacent openings and thus to practically form a continuous, unbroken, integral chain of openings around the circular face of the guard from one free end back 80 around again to the other free end. This purpose is accomplished in the construction of the guard by not separating or cutting the adjacent arms from each other at the connection 11. By this means of construction 85 the fan guard comprises a unitary, unbroken, continuous and integral structure, no soldering or other extraneous connecting means being necessary excepting at the two 90 free ends.

For the purposes of economy of construction as well as to form a balanced and attractive appearing device, it is advisable to have the arms divided as shown although it is obvious that they may be divided at other 95 points along their length without departing from the spirit of the invention. The relative number of arms is immaterial as they will be varied according to the size and use of the device. Furthermore certain of the 100 arms may be removed by cutting or otherwise, or other arms added without departing from the inventive idea. The device may of course be made of any desirable size. The shape of the device is immaterial as is the 105 size and shape of any of its parts. It is obvious that the principle of construction may be adopted for the making of inclosing devices of other shapes than round and for other purposes than that specifically described.

I do not restrict myself to any of the de-

tails as shown and described further than the scope of the appended claims demands.

I claim:

1. A guard for fans and the like having a front face comprising a central ring, and arms radiating therefrom, a rear face comprising a plurality of attachment means with arms radiating therefrom in groups and a central circular face integral with the 5 arms of the front and rear faces, the whole being formed of a single piece of expanded metal.
2. A guard for fans and the like having a front face comprising a central ring and 15 arms radiating therefrom, a circular chain-like face formed by splitting and expanding a portion of said arms and a rear face formed of a continuation of said arms, said arms at the rear being gathered in groups 20 to a plurality of attachment means, and said groups being spaced from each other to permit application of the guard, the whole being formed of a single piece of expanded metal.
- 25 3. A guard for fans and the like having a front face comprising a central ring and arms radiating therefrom, a circular face

formed by splitting and expanding a portion of said arms and a rear face formed of a continuation of said arms, said arms on 30 said front and rear faces being twisted to present their edges to the vertical plane of the guard, the whole being formed of a single piece of expanded metal adapted to substantially inclose the fan.

35 4. A guard for fans and the like comprising a series of arms integrally united at a common central point on one face of the guard and integrally united to a plurality of points on the other face of the guard, each arm being split to form an expanded opening and the adjacent arms being integrally united at a point adjacent said openings to form the edges of said openings into a continuous chain, said chain forming the 40 45 circular face of the guard.

In testimony whereof I have signed this specification in the presence of two subscribing witnesses.

THOMAS W. VARLEY.
